ADJUSTABLE EXTENSION SOCKET

Clarence Birdseye and Harold Douglas Wilson,
Gloucester, and Walter N. Heath, Rockport,
Mass., assignors to Birdseye Electric Corpora-
tion, Dover, Del., a corporation of Delaware

Application August 11, 1937, Serial No. 158,516

8 Claims. (Cl. 173—344)

This invention relates to extension sockets for the general purpose of making any desired adjustment as to size, location or angle between a fixture already installed or available and an electric lamp to be mounted therein. More particularly, the invention consists in an improved extension socket having an adjustable section of flexible non-resilient sheet metal which is effective at all times and in all positions of adjustment to enclose and protect the electrical connections contained in the socket and which will readily permit adjustment both axially and angularly.

The adjustable extension socket of our invention is particularly useful when used in connection with electric lamps having upon a part of the bulb area a reflecting coating designed to concentrate and direct the light of the lamp in a defined beam. When our adjustable extension socket is included in an installation, the lamp may be screwed into it and its flexible section may be then readily deformed so that the lamp may be held at the desired angle and its beam of light thus directed upon any selected area. When the lamp is used with an external reflector requiring close adjustment of the longitudinal or axial position of the lamp, this also is facilitated by the extension socket of our invention in that the flexible section thereof may be collapsed or elongated to bring the lamp into a position of focus.

An important feature of our invention consists in a tubular or sleeve-like section in an extension socket which is made of flexible, non-resilient sheet metal and includes a plurality of prominent circumferential corrugations, forming, in effect, a metallic bellows section. This presents the advantage that it may be easily and inexpensively manufactured and incorporated in the complete extension socket. As herein shown it is insulated from the electrical connections contained within the socket and is effective at all times as a protection for them.

In assembling the parts of the extension socket of our invention the end portions of the flexible bellows section are connected, with the interpolation of suitable insulating elements, at one end to a base member adapted to be inserted in any standard fixture and at the other end to a socket for a lamp base. Flanged sleeves or thimbles of insulating material are preferably, though not necessarily, employed for this purpose and these are so designed as to carry or support the metallic portions of the base and of the socket through

which connections are made with the fixture on the one hand and the lamp on the other hand.

These and other features of the invention will be best understood and appreciated from the following description of a preferred embodiment thereof selected for purposes of illustration and shown in the accompanying drawing in which,

Fig. 1 is a view in elevation, partly in section, of the component parts of the socket separated one from another, and

Fig. 2 is a view in side elevation showing the socket in use and in one position of angular adjustment, and

Figure 3 is a longitudinal sectional view of the socket.

The component parts of the socket will be first described and then the manner in which they are assembled in the complete article will be explained. One end of the socket comprises a metal base 10, spun of sheet metal with a thread rolled into its side walls and a slight flare in its open end, as is usual in a lamp base. The upper end of the base as shown in Figure 1 is closed by a cap or filler of insulating material 11 molded to shape and having a metal terminal disk or button 12 at the center thereof. While the base herein shown is threaded it may be shaped to fit any conventional form of fixture and to include correspondingly located terminals.

Designed to fit within the base 10 is an insulating sleeve 13 of porcelain, "Bakelite" or other plastic or ceramic material and this is provided at its lower end with a circumferential flange 14. The body of the flanged insulating sleeve is threaded to receive externally the thread of the base 10 and it is also provided with a longitudinal slot 15 which serves as a wire passage in the assembled socket. One or more fibre washers 16 and 17 are provided to fit over the body of the sleeve 13 and to register with the flaring end of the base 10.

The adjustable section of the socket comprises a sleeve 18 of thin flexible but non-resilient metal. It includes an end flange 19 which is arranged to fit over and enclose the flange 14 of the insulating sleeve 13. In the body of the metal sleeve are formed a plurality of deep but narrow circumferential corrugations 20. Below these corrugations 20 is a vertical flange 21 having a series of shallow circumferential corrugations rolled therein. The outside diameter of the deep corrugations 20 and the shallow corrugations in the flange 21 is substantially equal.

Beneath the sleeve 13 is shown in Fig. 1 a thimble 22 of porcelain, "Bakelite" or the like, hav-

ing a flat closed upper end and a series of circumferential ribs 23. The upper end of the thimble 22 is of such shape as to be received within the flange 21 of the metal sleeve 18 with its ribs fitting within the shallow corrugations thereof. The base of the thimble is provided with three perforations forming passages therethrough. Below the thimble is shown a metal cap 24 threaded to receive the base of a lamp and having a pair of screws 25 which are adapted to pass through the passages in the base of the thimble 22 to secure the cap in place. Finally there is shown in Fig. 1 a center terminal member 26 which in the assembled socket is secured in place in the bottom of the thimble 22 and spaced from the walls of the metal cap 24.

In assembling the parts above described to provide the adjustable extension socket of our invention, the flanged insulating sleeve 13 is first placed within the metal sleeve 18 with its flange 14 enclosed within the end flange 19 of the sleeve and its body projecting upwardly. The washers 16 and 17 are threaded upon or slipped over the body of the sleeve and clamped in place by having the base 10 screwed upon the threaded body thereof. The metal cap 24 and terminal 26 are assembled within the porcelain thimble 22 and then the base portion of the thimble having the circumferential ribs is inserted within the flange 21 of the metal sleeve 18 and the latter is spun or otherwise clenched to form a permanent connection with the thimble 22. Meanwhile, a lead wire 29 is extended from the center terminal 26 to the terminal disk 12 and connected thereto by solder 28. A second lead wire 30 is led from one side of the cap 24 through the metal sleeve 18, and through the longitudinal groove 15 of the insulating sleeve 13. It is then brought out between the two washers 16 and 17 and secured to the side of the base 10 by a drop of solder 27 thus completing the electric circuit of the socket.

In Fig. 2 the socket is shown in use, being screwed into a wall or ceiling socket 30, shown in dotted lines, and having a lamp 29 screwed into the metal cap 24. The lamp is shown as having a metallic coating over a portion of its inner wall so disposed as to direct the rays of the lamp in a defined and concentrated beam. The lamp as a whole is shown in a position of angular adjustment, inclined about 30° to the vertical. It will be understood that the extension socket as a unit may be screwed into any already-installed wall socket or the like and that the lamp may be screwed into the open end of the socket. Before or after the lamp is in place, the extension socket may be angularly adjusted by merely pressing its outer end in the desired direction, the flexible corrugations 20 acting as yielding bellows section.

Having thus described our invention, what we claim as new and desire to secure by Letters Patent of the United States is:—

1. An extension socket for lamps, comprising a conductive threaded base having an insulated contact thereon, a conductive lamp-receiving socket having an insulated contact therein, an intermediate section permanently united to the base and socket and having a plurality of flexible circular corrugations therein readily deformable to hold the socket in different positions of angular adjustment with respect to the base, and separate electrical connections from said base and its contact to the socket and its contact.

2. An adjustable extension socket for lamps, comprising a flexible non-resilient sleeve of sheet

metal having a retaining flange at each end, a support having a conductive threaded shell thereon and having an insulated connection with one flange on the sleeve, a metallic socket for a lamp having an insulated connection with the other flange of the sleeve and an electrical connection with the shell, and a central connection insulated from said metallic socket and having a terminal contact insulated from the shell.

3. An adjustable extension socket for lamps, comprising a flexible non-resilient sleeve of sheet metal having a plurality of flexible and non-resilient corrugations therein, a threaded metallic base projecting beyond one end of said sleeve and presenting an insulated end terminal, an insulated thimble projecting beyond the other end of said sleeve and containing a lamp receiving socket electrically connected to said base and a center connection associated with said socket and electrically connected to the insulated terminal of the base.

4. An adjustable extension socket for lamps, comprising a tubular metallic bellows section having an inturned flange at one end, a threaded insulating sleeve having a flange enclosed by said metallic section and engaged with the flange thereof, a metallic base threaded upon said sleeve and acting to draw the two flanges into contact, a terminal insulated from said metallic base and electrical conducting lamp engaging members carried by said metallic section and insulated therefrom and electrically connected to the base and to the terminal.

5. An adjustable extension socket for lamps, comprising a tubular metallic bellows section having an inturned flange at one end, a threaded insulating sleeve having a flange covered by the flange of the metallic section, a washer insulation encircling the insulating sleeve, a metallic base threaded upon said sleeve and acting to clamp said washer between itself and the flange of the metallic section, a terminal insulated from said metallic base, a lamp receiving member having two electrical conducting portions held by the other end of said section and electrical connections including a wire attached at one end to one of said portions, passing out through said washer insulation and attached at its other end to said base and a second electrical connection between the other of said portions and the terminal insulated from the base.

6. An adjustable extension socket for lamps, comprising a flexible bellows section having an inturned flange at its upper end, a flanged insulating sleeve having a threaded upwardly extending stem passing out through said flange, a metallic base threaded upon said stem and serving both to clamp the sleeve and bellows section together and to supply means for engaging the socket with a fixture, an insulated end terminal carried by the base and a lamp socket carried at the lower end of the bellows section and having independent electrical connections from it to the base and to said end terminal.

7. An adjustable extension socket for electric lamps, comprising a threaded base, an end terminal insulated therefrom, a lamp receiving socket having a center connection associated therewith, and an intermediate tubular portion connected to the base and socket and being of flexible non-resilient sheet metal with circumferential corrugations therein and being readily deformable whereby the base and socket may be bent with respect to each other, the socket and its center

connection being separately electrically connected to the base and its end terminal.

8. An adjustable extension socket for electric lamps, comprising a base shaped to fit a conventional fixture and including terminals, a lamp receiving socket having terminals, and an intermediate tubular portion connected to the base and socket and being of flexible, non-resilient, material with circumferential corrugations there-

in, and being deformable whereby the base and socket may be bent at an angle with respect to each other, and means for electrically connecting the terminals of the base with those of the socket.
